CAR COUPLER SUPPORTING MEANS

William J. Metzger, Euclid, Ohio, assignor to National Malleable and Steel Castings Company, Cleveland, Ohio, a corporation of Ohio

Application July 24, 1940, Serial No. 347,342

8 Claims. (Cl. 213—14)

This invention relates to support means for car couplers and more particularly to means for resiliently supporting a coupler while permitting horizontal and vertical angling thereof.

An object of my invention is to provide coupler carrier means which during disassembly thereof is readily removable from the carrier iron without necessitating the removal of the coupler or draft rigging.

Another object is to provide means associated with the coupler supporting means adapted to support the train service lines independently of the coupler so that the lines are not subjected to longitudinal or vertical movement as occurs in service when the lines are connected to the coupler.

Another object is to provide coupler supporting means comprising a carrier iron so shaped that the shifter member may be mounted thereon to cooperate therewith in such a manner that the shifter member is positively maintained in assembled relation with the carrier iron and in which a support member is resiliently carried by said shifter member for supporting the coupler.

My invention moreover contemplates a construction wherein the support member is adapted to follow the vertical movements of the coupler shank throughout the normal range of movement thereof to thereby prevent undesired hammer blows of the shank on the support member due to the shank lifting clear of the member.

Further objects and advantages of my invention will be apparent from the following description taken in conjunction with the drawings in which:

Figure 1 is a side elevational view of the coupler support means.

Figure 2 is a plan view partly in section of the construction shown in Fig. 1.

Figure 3 is a front view partly in section of the construction shown in Fig. 1.

Figures 4 and 5 are fragmentary views showing modifications of my invention.

Figure 6 is a front view partly in section of a modified form of the invention.

Figure 7 is a plan view partly in section taken on line 7—7 of Fig. 6; and

Figure 8 is a partial side elevational view showing the attachment to the carrier iron of the form shown in Figure 6.

Referring to the drawings, there is shown a member 10 fastened to the car frame and comprising a carrier iron 11, a horizontal top portion 12, and vertical connecting columns 13.

From each of portions 13 projects an arm 14 to which is fastened a bail mounting bracket 15. In accordance with my invention there is provided a shifter or saddle member 16 slidably mounted on the carrier iron 11. This member is adapted to slide transversely on the carrier iron in response to horizontal angling of the coupler. In order to secure stability in the mounting of the saddle member on the carrier iron, the carrier iron is preferably H-shaped in section and comprises top flanges 17 and 18, central web 19, and lower horizontal portion 20. The vertical columns 13 which merge with the carrier iron are likewise H-shaped in section. While the preferred embodiment of my invention utilizes a carrier iron H-shaped in section, other modifications thereof may be used, as will be hereinafter described. The base portion 21 of the saddle member extends substantially the length and width thereof to provide a large carrier iron engaging surface 22, thus lessening the rate of wear on the contacting surfaces. Depending from the inner side of base portion 21 is an L-shaped flange 23 which extends into overlapping relation with flange 18 to limit upward as well as forward movement of the saddle member. The front side of the base portion has a depending flange 24 adjacent flange 17, thus limiting any rearward movement of the saddle member. Secured to the front side of the saddle member by means of bolts 25, is a lock piece 26 which is provided with L-shaped portions 27 overlapping flanges 17 and 24. It will be clear therefore that with lock-piece 26 in place, accidental displacement of the saddle member from the carrier iron is effectively precluded. In service, lock-piece 26 can be subjected only to a downward force upon upward movement of the saddle member and any such force is transmitted by the offset portion 28 thereof to the saddle member, thereby relieving bolts 25 of any shearing stresses. Also, with this arrangement the saddle member is effectively guided along the carrier iron as it moves transversely during horizontal angling of the coupler.

Resilient supporting of the coupler is accomplished through the use of coil springs mounted on the saddle member. At each end of the saddle member are provided upwardly extending housings 30, each receiving and partially enclosing a spring 31. Each of housings 30 comprises a side wall 32 and front and rear walls 33 and 34 respectively. Each spring 31 rests on a seat 35 and is positioned with respect thereto by a boss 36. The coupler is supported on springs 31.

by means of a support member 37 comprising a central portion 38 underlying the coupler shank 39 and upwardly and outwardly extending arms 40 which are adapted to be received in housings 30. Each arm is formed with a side wall 41, front and rear walls 42 and 43 respectively, and a top connecting wall 44 engaging the spring. Top wall 44 is formed with a depending boss 45 adapted to position the upper end of each spring with respect thereto. Bolts 46 and nuts 47 maintain the springs and shifter member in assembled relation with the saddle member, and also by means thereof the initial compression of the springs may be adjusted to bring the coupler into correct operating position. A wear plate 48 is interposed between the coupler shank and portion 38 of the support member. It will be observed that lateral movement of the coupler shank with respect to the support member is limited due to the comparatively small clearance between the vertical walls of the shank and arms 40, as at 49, so that the shank is centered with respect to the springs, thereby placing each spring under substantially the same load at all times during horizontal angling of the coupler. By this arrangement portion 38 of the support member will remain in a horizontal position in engagement with the under-surface of the shank. In order to stabilize transverse movement of the support member with respect to the saddle member, inward projections 50 are provided on side walls 32 of housings 30. Each of projections 50 is adapted to engage the side of one of the springs so that each boss 45 is received within its associated spring in such a manner that any clearance between the boss and the portion of the coils adjacent wall 32 of the saddle member is taken up. In this manner, with each boss in engagement with the coils, transverse movement of the support member relative to the saddle member is cushioned by the resistance to bending of that part of the springs above the projections 50. Also, the projections may be made to extend inwardly sufficient to bow the springs slightly to assure tight engagement of each boss with the coils adjacent walls 32.

Projecting rearwardly from the saddle member are lugs 51 and 52 to which are secured the train service lines support brackets 53 and 54 respectively. The service lines (shown in dot-dash) are secured to their respective brackets by clamps 55 and 56. It will be clear that with this arrangement the train service lines are mounted independently of the coupler and therefore are not subjected to longitudinal or vertical movement, as would occur in service if the lines were connected to the coupler.

To disassemble the support means from the carrier iron, lock-piece 26 and clamps 55 and 56 are first removed. The coupler is then raised an amount sufficient to permit the saddle member to be tilted rearwardly so that flange 24 will clear the top of the carrier iron. The saddle member can then be moved rearwardly from the carrier iron. Assembly of the mechanism is accomplished by applying the preceding steps in reverse order.

In the modification shown in Fig. 4 the carrier iron 60 is formed with vertical webs 61 joined by a horizontal top flange 62, the sides of which project past the webs, as at 63. The saddle member 64 is similar to the saddle member 16 of the previous embodiment and cooperates with the carrier iron in like manner.

In Fig. 5 the carrier iron 70 is substantially U-75

shaped in cross section, with outwardly extending top flanges 71 upon which is mounted a saddle member 72. Forward as well as rearward movement of the saddle member with respect to the carrier iron is limited by a depending longitudinal central flange 73. This flange is received between the vertical webs 74 of the carrier iron and guides the saddle member as it moves transversely of the carrier iron. Accidental upward displacement of the saddle member is precluded by lock-piece 75 as in the previous embodiments. Lug 76 extending rearwardly from the saddle member provides means to which the train service line support bracket may be secured.

In Figs. 6, 7, and 8 is shown a modification of my invention wherein the support member is caused to follow the movement of the coupler shank by means of auxiliary springs, thus eliminating noise caused by contact of the coupler shank with the support member after the two have separated during normal vertical angling of the shank. In this embodiment saddle member 80 is adapted to slide along the carrier iron 11 as in the previous form of the invention and has an L shaped flange 81 extending into overlapping relation with flange 18 of the carrier iron. On the opposite side from flange 81 is a depending flange 82 and a lock piece 83 secured to the saddle member in the same manner as before.

Extending upwardly from each end of saddle member 80 is a spring housing 84, each comprising a side wall 85 and front and rear walls 86 and 87 respectively. A spring 88 in each housing rests upon a seat 89 and is positioned by a boss 90. Coupler shank 39 rests on a support member 91 which has upwardly and outwardly extending arms 92 received in spring housings 84 and resting on the upper ends of springs 88. Each arm is formed with a side wall 93, front and rear walls 94 and 95 respectively, and top wall 96 engaging one of springs 88. Extending downwardly from top wall 96 is a spring housing 97 adapted to receive a spring 98. Bolt 99 and nut 100 maintain springs 88 and 98 under the desired amount of compression. It will be observed that the pressure of spring 88 is transmitted to spring 98 through housing 97, thus as spring 88 is further compressed by the coupler, spring 98 is released and vice versa.

Moreover, the pressure-travel characteristics of springs 88 and 98 are such that the coupler shanks may be adjusted to a normal horizontal position by releasing or tightening nut 100.

During operation of the car over substantially level track the coupler shank may normally angle vertically to such an extent that the vertical movement thereof where it contacts support member 91 is from about one-half inch to one inch. Greater vertical angling of the shank may take place on very uneven track or in passing over the top or bottom of grades. If during the aforesaid normal vertical angling, the coupler shank separates from support member 91, the contact between the shank and member, following such separation, may be so severe as to result in undesirable noise.

In the arrangement shown in Figs. 6, 7, and 8 spring 88 expands, during normal upward vertical angling of the coupler, against the pressure of spring 98 and thus member 91 remains in contact with the shank during said normal vertical angling. In the construction illustrated contact between the shank and support member is maintained only during normal vertical angling of the coupler as substantially all the objectional noise

would occur during this movement. However, by selecting springs of suitable pressure-travel characteristics contact could be maintained over the maximum amount of vertical angling of the coupler.

In addition to prevention of noise as above set forth, spring 98 absorbs shocks on nut 100 incident to sudden upward movement of support member 91.

As in the first embodiment of the invention means is provided to cushion lateral movement of support member 91 relative to saddle member 80 caused by forces insufficient to move the saddle member on carrier iron 11. Failure to cushion said movement results in undesirable noise due to contact between the ends of walls 94 and 95 of member 91 and walls 85 of member 80. Opposite each of walls 94 and 95, and spaced therefrom, is a projection 101 extending inwardly from walls 85. Lateral movement is cushioned by the resistance offered by springs 88 between the point of contact 102 of the lower end of the spring and boss 90, and the point of contact 103 of the lower end of housing 97 with spring 88. This latter point of contact will vary as the coupler shank moves vertically and housing 97 moves relative to spring 88. It will be observed that each projection 101 has a sloping surface 104 and each opposite wall 94 and 95 has a correspondingly sloping surface 105. As support member 91 moves downwardly the clearance between surfaces 104 and 105 is reduced at the same time that the vertical distance between contact points 102 and 103 becomes less. Hence, the amount of lateral movement of member 91 relative to member 80 decreases with a decrease in the length of spring 88 available to resist said movement and overstressing of the spring is prevented.

If desired a projection similar to projection 50 of Figs. 2 and 3 may be used in the embodiment shown in Figs. 6, 7, and 8 in which case sufficient clearance should be provided between housing 97 and spring 98 to permit flexing of spring 88.

The terms and expressions which I have employed are used as terms of description and not of limitation, and I have no intention, in the use of such terms and expressions, of excluding any equivalents of the features shown and described or portions thereof, but recognize that various modifications are possible within the scope of the invention claimed.

What I claim is:

1. In a car coupler supporting mechanism, a carrier iron beneath the coupler, a saddle member mounted on said carrier iron and shiftable thereon in response to horizontal angling of the coupler, means on said member embracing said carrier iron to prevent displacement of said member from said carrier iron, spring housings at each end of said member, springs in said housings, a coupler supporting member supported on said springs, and means within each housing engaging said springs below the tops thereof adapted to limit transverse movement of said springs in one direction with respect to said member.

2. In a car coupler supporting mechanism, a carrier iron beneath the coupler, a saddle member mounted on said carrier iron and shiftable thereon in response to horizontal angling of the coupler, spring means on said saddle member, a support member spaced vertically from said carrier iron for supporting said coupler from said spring means, retaining means passing through said support member and spring means, and resilient means reacting between one end of said

5 retaining means and said support member adapted to cushion upward movement of the latter.

3. In a car coupler supporting mechanism, a carrier iron beneath the coupler, a saddle member mounted on said carrier iron and shiftable thereon in response to horizontal angling of the coupler, spring means on said saddle member, a support member spaced vertically from said carrier iron for supporting said coupler from said spring means, and means for resiliently adjusting the compression of said spring means, said means comprising a retaining member extending through said saddle member, and auxiliary spring means reacting between said retaining member and said support member adapted to cushion upward movement of the latter.

4. In a car coupler supporting mechanism, a carrier iron beneath the coupler, a saddle member mounted on said carrier iron and shiftable thereon in response to horizontal angling of the coupler, spring means on said saddle member, a support member spaced vertically from said carrier iron for supporting said coupler from said spring means, a spring housing at each end of said support member, a spring in each of said housings, retaining means passing through said saddle member and housing, and resilient means between said support member and retaining means adapted to cushion upward movement of said support member.

5. In a car coupler supporting mechanism, a carrier iron beneath the coupler, a saddle member mounted on said carrier iron and shiftable thereon in response to horizontal angling of the coupler, spring means on said saddle member, a support member spaced vertically from said carrier iron for supporting said coupler from said spring means, a housing depending from each end of said support means into said spring means, a spring in each housing, and adjustable retaining means passing through said saddle member, housings and said springs, said retaining means being adapted to compress said springs within said housings to lower said support member during positioning of said coupler in a vertical direction.

6. In a car coupler supporting mechanism, a carrier iron beneath the coupler, a saddle member mounted on said carrier iron and shiftable thereon in response to horizontal angling of the coupler, spring means on said saddle member, a support member spaced vertically from said carrier iron for supporting said coupler from said springs, a housing depending from each end of said support means into said spring means, a spring in each housing, and means normally maintaining said last named spring under compression, said spring being adapted to expand upon downward movement of the coupler and to compress upon upward movement thereof to enable said support member to remain in engagement with said coupler.

7. In a car coupler supporting mechanism, a carrier iron beneath the coupler, a saddle member mounted on said carrier iron and shiftable thereon in response to horizontal angling of the coupler, spring means on said saddle member, a support member spaced vertically from said carrier iron for supporting said coupler from said spring means, said support member being adapted to move transversely with respect to said saddle member, and means including a projection on said saddle member adapted to engage said spring means to limit said transverse movement of said support member.

8. In a car coupler supporting mechanism, a carrier iron beneath the coupler, a saddle member mounted on said carrier iron and shiftable thereon in response to horizontal angling of the coupler, spring means on said saddle member, a support member spaced vertically from said carrier iron for supporting said coupler from said spring means, said support member being adapt-

ed to move transversely with respect to said saddle member, means including said spring means adapted to cushion said transverse movement of said support member, and means constructed and arranged to decrease the amount of said transverse movement upon downward movement of the coupler.

WILLIAM J. METZGER.
